UNITED STATES PATENT OFFICE.

WILLIAM F. HUTCHINSON, OF LYNN, MASSACHUSETTS, ASSIGNOR TO MARY E. HUTCHINSON, OF SAME PLACE.

TOOTH-PICK MACHINE.

SPECIFICATION forming part of Letters Patent No. 404,282, dated May 28, 1889.

Application filed September 3, 1887. Serial No. 248,767. (No model.)

To all whom it may concern:

Be it known that I, WILLIAM F. HUTCHINSON, a citizen of the United States, residing at Lynn, in the county of Essex and State of Massachusetts, have invented a new and useful Tooth-Pick Machine, of which the following is a specification.

My invention relates to improvements in tooth-pick machines in which a ribbon or strip 10 of wood from which the tooth-picks are cut is passed between revolving cylinders, one of which is provided with a series of knives; and the objects of my invention are, first, to provide a very rapid-working machine; second, to provide a machine that will make all the tooth-picks of equal size, and, third, to provide a machine that will not waste the material. I attain these objects by the mechanism illustrated in the accompanying drawings, in which—

Figure 1 is a side view of the entire machine; Fig. 2, an end view of the same; Fig. 3, a plan of the spacers which regulate the distance between the knives; Fig. 4, a side 25 view of one of the spacers; Fig. 5, a side view of one of the knives; Fig. 6, an enlarged section of the knives and spacers on the line $y-y$; Fig. 7, a sectional view of the machine as shown in Fig. 2 on the line $y''-y''$; Fig. 8, a 30 sectional view of Fig. 1 on the line $y'-y'$; Fig. 9, a plan of the flanges of the drum, showing slots through which the knives and spacers are inserted to be fastened into the machine; and Fig. 10, a perspective view of the spring-fingers which are fastened to the flanges and extend between the knives.

Similar letters refer to similar parts throughout the several views.

The machine consists, essentially, of the 40 two drums A and B, the upper drum, A, operating as a cutter and the lower drum, B, as a bearing for the knives. These drums are hung in the frame C upon the shafts D and E, the upper shaft, D, being provided with pulleys 45 G and H for operating the machine. The larger drum, A, is turned from a single piece of iron, and is provided with flanges $f-f$, one on each end. These flanges are fastened to the ends of the drum A by the bolt h , so that 50 they may be tightened or loosened, and are beveled upon the inside portion that projects

above the drum A to correspond in shape to the ends of the spacers a and knives a' . They are also provided with a slot or opening, c , as shown in Fig. 9, through which the spacers a and knives a' may be inserted. The spacers a are made of the same width as a tooth-pick, and are to be placed between the knives. The knives a' are made of thin strips of steel, with ends of the same shape as the spacers a (see Figs. 4 and 5) and as the inside bevel of the flanges $f-f$. (See Fig. 7.) The spacers and knives are placed and fastened in position upon the drum A as follows: A knife, a' , is first inserted through the slot c of the flanges $f-f$, 60 then a spacer, a , is inserted, and so on alternately until the flanges are full, the drum A making a solid backing for the knives and spacers. The flanges $f-f$ are then tightened by screwing up the bolts h , and the knives and 65 spacers are securely held in the position shown in Fig. 8, their backs to the drum A and the knives just the width of a spacer or tooth-pick from each other. The lower drum, B, is composed of rubber or rawhide, and is held 70 in position upon the shaft E by the collars d and e .

Beneath the bearings F of the shaft E is a bolt, e' , the object of which is to raise the drum B as it becomes worn by the action of 75 the knives of the upper drum, A. The tooth-picks are cut from thin veneers of wood, which are turned from the log in long lengths in a manner well known to the trade. The width of the veneer corresponds to the length 80 of the tooth-pick. These veneers are passed between the drums A and B, when they are rapidly cut into tooth-picks by the knives a' , which revolve with the drum A. In order that the tooth-picks may not stick between 85 the knives a' , a series of steel springs, b , with fingers b' , are fastened to the flanges $f-f$ by the screw s , the fingers of the springs $b-b'$ extending between each knife and the surface 90 of the fingers should be flush with the cutting-edge of the knives a' , so that when a tooth-pick is cut a finger of the spring will be depressed, and, springing back immediately into place, will expel the tooth-pick from 95 between the knives. I do not confine myself 100 to the spring shown, as any suitable spring may be used.

It will be seen that with my machine no feeding mechanism is needed. A strip of veneer being placed between the drums A and B, a tooth-pick will not be cut till a knife reaches a central point between the two drums, and when this is cut the next knife will have taken hold of the veneer, and so on, the machine thus doing its own feeding. It will be seen, also, that by having the knives a' equi-distant around the entire periphery of the drum A there is no waste of material, every cut making a tooth-pick.

Instead of the spacers a , grooves the width of a tooth-pick apart may be cut across the drum A and the knives a' placed in the grooves and fastened by the flanges $f f$, as heretofore described.

Having fully described my invention, what I claim, and desire to secure by Letters Patent, is—

1. A tooth-pick machine having the drum A, with the spacers a and knives a' arranged around its periphery, and suitable springs between said knives, in combination with the drum B, substantially as shown and described. 25

2. The flanges $f f$, beveled as shown and provided with the slot c , in combination with the knives a' and drum A, substantially as shown, and for the purpose described.

3. A tooth-pick machine having the drum 30 A, with the knives a' arranged around its periphery, and suitable springs between said knives, in combination with the drum B, substantially as shown and described.

WILLIAM F. HUTCHINSON.
